UNITED STATES PATENT OFFICE.

FRED C. PARKER, OF TAUNTON, MASSACHUSETTS.

FOOT-REGISTER.

No. 911,436.

Specification of Letters Patent.

Patented Feb. 2, 1909.

Application filed July 13, 1908. Serial No. 443,342.

To all whom it may concern:

Be it known that I, FRED C. PARKER, a citizen of the United States, and a resident of Taunton, in the county of Bristol and Commonwealth of Massachusetts, have invented a new and Improved Foot-Register, of which the following is a full, clear, and exact description.

The invention has for its object to provide 10 a register in the floor of a room that is heated by a system of steam or hot-water heating, by means of which one may warm his feet or any other object he may place thereon, which cannot be done with any register now 15 in use with either a system of steam or hot-water heating.

The invention consists in the novel construction and arrangement of parts, as hereinafter described and claimed.

20 In the drawings hereto appended, Figure 1. is a top view, of my invention, Fig. 2. is a sectional view thereof on the line *f*—*f* in Fig. 1., and Fig. 3. is an end view of my invention.

25 Reference being made to the drawings, in which similar numbers refer to corresponding parts of all the figures,—1 is a metal box, which depends in an aperture 2 in the floor 3 of a room. The edge of floor 3 is formed 30 into a recess 4, into which fits a flat grating 5, having a border 6 of solid metal, said border 6 projecting beyond the edge of an annular rim 7, which is formed around the top of the box 1. A second recess 8 is formed, below 35 recess 4, in the floor 3, into which fits annular rim 7, the lower surface of rim 7 resting upon the upper surface of recess 8, which thus forms a support for the box 1. A mat 40 of asbestos 9 or of other material which is a poor conductor of heat, co-extensive with the top surface 10 of box 1 is laid upon that surface, and a thin sheet of copper or other metal 11, likewise co-extensive with the top of box 1, is super-imposed on mat 9 and grating 5 is placed on top of metal sheet 11 so 45 that the top of grating 5 is flush with the top of the floor 3.

Set in the wall 12 of box 1 are screw-pegs 13 which project above the top surface 10 of box 1 a distance equal to the combined thickness of mat 9, metal sheet 11, and $\frac{1}{2}$ the thickness of border 6 of grating 5. In the lower surface of border 6 are holes 14 registering with the tops 15 of pegs 13, which 55 also pass through holes 16 in the metal sheet 11 and holes 17 in the mat 9, thus preventing

lateral movement, relatively to one another, of box 1 mat 9, metal sheet 11, and grating 5.

In the bottom wall 18 of box 1, preferably near a corner thereof, is an aperture 19, 60 registering with the open end of a pipe 20, which is connected with the boiler of a heater (not shown) and through which a fluid heating-medium is introduced into box 1. On pipe 20 is a shut-off valve 21, operated 65 by a handle 22.

In the center of bottom wall 18 of box 1 is an aperture 23 through which a pipe 24 passes vertically, having its upper end 25^a open, inside box 1, and situated a short distance below the upper wall 26 of box 1, and at its lower end, outside the box 1, provided with an air-valve 27, operated by a handle 28. A second pipe 29, the open end of which registers with an aperture 30 in the 75 bottom wall 18 of box 1 at the corner opposite to aperture 19, is employed to convey the heating medium from the box back to the heater (not shown).

When one desires to use my invention, he 80 must open air-valve 28 as well as valve 21 in order to allow the fluid heating-medium flowing through pipe 20 to entirely fill the box 1 and thus come in contact with the top wall 26 of the box; otherwise, the air will 85 become imprisoned in the upper part of the box and very little heat will be communicated to the grating 5.

While I have described one form of apparatus which embodies my invention, I do 90 not wish to be understood as limiting myself to this form, but realize that there may be variations thereof, all embodying the principles employed in my invention. For example, when my invention is used on the 95 upper floors of a building, it may be found desirable to have the pipes enter through the sides of the box and the air-valves might be placed in the side walls of the box, instead of in the bottom. It may also be 100 found desirable to omit the mat 9, the metal sheet 11, and the grating 5, or any one of them.

Having now described my invention and its method of operation, what I claim as new 105 and desire to secure by Letters Patent, is,—

In a system of heating for a building employing a fluid heating medium, the combination of a box seated in an aperture in the floor, entirely closing said aperture so as 110 to prevent all passage of air therethrough, having one unpartitioned, oblong chamber

therein, a layer of heat-resisting material removably placed upon the top of said box, a sheet of metal thereon, and a grating superimposed over all, the top of the grating being substantially on a level with the top of the floor, means for introducing the heating medium into said chamber, means for conducting said medium from said chamber, and an outlet valve in the wall of said chamber for the purpose of allowing air to escape therefrom, substantially as and for the purpose set forth.

FRED C. PARKER.
